LUTHER F. BROBERG, OF CEDAR RAPIDS, IOWA.

AUTOMATIC WATER HEATER.

Application filed June 11, 1925. Serial No. 36,429.

This invention relates to automatic water heaters, and more particularly to that type of heaters known as instantaneous heaters.

The principal object of this invention is to provide an instantaneous water heater wherein the water is heated by burning gas, and wherein the usual pilot light is dispensed with.

Another object of this invention is the provision of automatic means for initiating a flow of gas and then igniting same, and terminating the ignition at a predetermined length of time after the gas has started flowing.

Another object of this invention is the arrangement in connection with the mechanism for initiating, igniting and burning a flow of gas, of electrical actuating mechanisms, arranged to be controlled by the flow of water after a valve has been opened in the water line.

Another object of this invention is the provision of electrical connections and mechanisms for terminating the flow of burning gas, arranged to be controlled by stopping the flow of water after a valve has been closed in the water line.

A further object of this invention is the arrangement in connection with the mechanism for stopping the flow of gas after the flow of water has been stopped, of automatic safety means for also terminating the flow of burning gas in the event of premature cessation of electric current.

Other objects and advantages will be apparent from the following description, wherein reference is made to the accompanying drawings illustrating a preferred embodiment of my invention and wherein similar reference numerals designate similar parts throughout the several views.

In the drawings:

Fig. 1 is a front elevation of a water heater embodying my invention.

Fig. 2 is an enlarged elevational view of the lower portion of the water coil, gas burner, and electrical actuating mechanisms, the several mechanisms being shown in their

normal positions, i. e. as they would appear when the heater is idle and the valve in the water line closed.

Fig. 3 is a similar view showing several of the electrical mechanisms in the positions assumed while the gas and water are flowing.

Fig. 4 is a detail sectional view taken substantially on the line 4-4 of Fig. 2.

Fig. 5 is a diagrammatic view illustrating the several circuits utilized for actuating the several electrical mechanisms, and

Fig. 6 is a rear elevation of the lower portion of the heater.

Referring now to the drawings, the numeral 5 designates a casing of a water heater surrounding a copper coil 6 and gas burner 7. These elements may be the same as ordinarily used in gas water heaters, or constructed in any desired way. One extremity of the copper coil 6 is connected through the outlet pipe 8 with a faucet 9, which is intended to represent any faucet of the usual household water system. The other extremity of the copper coil 6 is connected through the inlet pipe 10 with the city reservoir or an elevated storage tank so that the water supplied to the coil 6 is under pressure tending to maintain the coil filled. As best shown in Fig. 2 a valve 11 is arranged in the inlet pipe 10 to control the flow of water from its source to the coil 6. This valve 11 seats upon a flange 12 within the vertical pipe section 13 whenever the water pressures on opposite sides of the valve are substantially equal, a light spring 14 being arranged to force the valve 11 downwardly into engagement with the flange 12 at such times. This occurs, for example, whenever the faucet 9 is closed, the water from the reservoir completely filling the outlet pipe 8 and coil 6 until the pressure on the upper side of the valve 11 is substantially equal to the pressure on the lower side of the valve. Then whenever the faucet is opened the pressure on the upper side of the valve is lessened and the pressure of the water against the lower face of the valve 11 will lift the valve from its seat

90
95

upon the flange 12, and the water will flow through the inlet pipe 10 into the coil 6 and thence to the faucet. This automatic lifting of the valve 11 is utilized to initiate the action of several electrical mechanisms and ignite the gas at the gas burner 7, as hereinafter described. A master switch including the stationary contact 15 and movable contact 16 is held in open position by the valve stem 11^a whenever the valve 11 is in closed position, an insulated block 11^c on the lower extremity of the valve stem resting upon the movable contact 16 and forcing it away from the set screw 17 carried by the stationary switch member 15 (note Fig. 2). When, however, the valve 11 is lifted by the incoming water the block 11^c is moved upwardly permitting the movable contact 16 to engage the set screw 17 and complete a circuit through the stationary switch member 15. Upon the closing of the master switch the solenoid coil 18 is energized to draw its armature 19 from the position shown in Fig. 3 against the tension of the coil spring 20 surrounding the outer portion of the armature and abutting at its extremities against the fixed bracket 21 and the adjustable tensioning plate 22 fixed upon the armature. The circuit for energizing the solenoid 18 is best shown in Fig. 5, a wire 23 extending from the fixed switch member 15 to and through the solenoid coil 18 and thence to the slidable switch member 24, which switch member is adapted to engage within the spring switch prong 25 when in its outer position. The switch prong 25 is directly connected by the wire 26 with the outlet wire 27. The inlet wire 28 leads directly to the movable switch contact 16 of the master switch, and accordingly, whenever the master switch is closed and the slidable switch member 24 engages the switch prong 25 the current can pass through the solenoid coil 18, and draw the armature 19 inwardly. In such inward movement the armature 19 moves the slidable switch member 24 out of engagement with the switch prong 25 and so breaks the circuit energizing the solenoid 18. This movement of the slidable switch member 24 is accomplished by the engagement of the insulated arm 29 with the inner lug 30 extending upwardly from the slidable switch member. As best shown in Fig. 4 the arm 29 extends laterally from the spring adjusting plate 22 carried by the armature 19 and extends in the path of the lugs 30 and 31 upon the slidable switch member 24 as well as into position to engage the upper extremity 32 of the pendulum 33 utilized in the timing of the ignition mechanism, as hereinafter described. Another insulated arm 32^a extends laterally from the armature 19 into the space between the bifurcated arms 33^a of the gas valve lever 34 (note Figs. 2-4) controlling

the position of the gas valve 35 arranged adjacent the lower extremity of the gas supply pipe 36 whereby the gas burner 7 is fed. When the gas valve lever 34 is in the position shown in Fig. 2 the valve is closed and no gas can pass to the burner. When, however, the armature 19 is drawn into the solenoid 18 upon the closing of the master switch the lateral arm 32 on the armature engages the gas valve lever and swings it to substantially the position shown in Fig. 3, opening the valve in so doing to permit the flow of gas to the burner.

Simultaneously with the energization of the solenoid 18 to attract its armature 19 the primary winding of the transformer coils 37 and 38 are energized and thereupon attract the pivoted armature 39, swinging it from the position shown in Fig. 2 to the position shown in Fig. 3 against the tension of the coil spring 40. The upward swinging movement of the armature 39 is utilized to effect a latching of the armature 19 in its innermost position, as shown in Fig. 3. A latch 41 is pivotally mounted upon the free extremity of the armature 39 and carries at its upper extremity a roller 42 adapted to enter a notch 43 in the inner extremity of the armature 19. By virtue of this construction the movement of the slidable switch member 24 away from the switch prong 25 to break the circuit energizing the solenoid 18 will not serve to immediately return the armature 19 to its outermost position, because the latch member 41 engages in the notch 43 of the armature 19 as long as the swinging armature 39 of the transformer coils remains in elevated position, and, of course, such elevated position is dependent upon the continuation of the flow of current through the transformer coils. The circuit for energizing the primary winding of the transformer coils comprises a wire 44 leading from the stationary master switch contact 15 to one of the transformer coils, thence to the other coil and thence to the outlet wire 27 (note Fig. 5). The inlet wire 28 is directly connected with the movable master switch contact 16 so that the circuit is completed to energize the transformer coils as long as the movable switch member 16 engages the stationary contact 15.

The transformer coils 37 and 38 are utilized to provide a low voltage current to the ignition mechanism, whereby the gas flowing from the burner 7 is automatically ignited, serving as a step down transformer to supply a low voltage current for operating the spark coil 45. The spark coil 45 may be of any desired construction, and the spark coil utilized in Ford automobiles has been found to satisfactorily operate in my improved heater. The passage of current through the primary winding of the transformer coils 37 and 38 upon closing of the master switch 130

causes a low voltage current to pass from the secondary winding of the transformer coils to the primary winding of the spark coil 45, causing an induced current of high potential to flow from the secondary winding of the spark coil to the spark plug 46, where sparks pass across the spaced terminals 46^a and 46^b whenever the automatic vibrator 33 engages the spring contact members 47 and 48 mounted at opposite sides of the vibrating pendulum 33. As hereinbefore described, the gas valve 35 is opened by the movement of the solenoid 18, and such movement is also utilized to set in motion the vibrator 33 of the ignition mechanism. The laterally projecting arm 29 engages the upper extremity 32 of the pendulum 33 as the armature 19 is attracted within the solenoid 18, tilting such pendulum until the arm 29 can pass thereover to the position shown in Fig. 3. This tilting of the pendulum 33 sets the pendulum vibrating for a predetermined length of time dependent upon the extent of tilt given the pendulum as well as upon the position of the center of gravity of the pendulum relatively to its fulcrum. As the pendulum vibrates it alternately engages the spring contacts 47 and 48 which are connected in series in the secondary circuit of the transformer coils 37 and 38, thereby forming a single pole switch and turns the current into the primary winding of the spark coil 45 upon the oscillation of the pendulum 33, causing an intermittent current through the spark coil and onward by induction to the spark plug 46. This intermittent passage of the current from the secondary winding of the transformer through the spark coil continues until the pendulum has narrowed its vibration to such an extent as no longer to engage the spring contacts 47 and 48. The weighted end of the pendulum 33 may be adjusted up or down so as to allow the desired timing of the oscillations of the pendulum and a sure and positive contact with the spring contacts 47 and 48. The circuit for intermittently firing the spark plug 46 for a predetermined length of time comprises the secondary winding 49 of the transformer coils, connected at one extremity by the wire 50 with the spring contact pieces 47 and 48 and connected at its opposite extremity through the wire 51 and spring bracket 52 with the primary coil 53 of the spark coil 45. One terminal 46^a of the spark plug is also connected through the wire 54 with the secondary winding of the transformer. The other terminal 46^b of the spark plug is connected through the wire 55 with the secondary winding of the spark coil. The pendulum 33 is also connected, as by the wire 56, with one of the terminals of the spark coil. Accordingly, no current passes to the spark coil from the transformer winding 49 except when the pendulum 33 engages either of the spring

contacts 47 and 48, and sparks will pass between the terminals 46^a and 46^b of the spark plug intermittently during the vibration of the pendulum.

By properly positioning the adjustable weighted end of the pendulum 33 and giving a sufficient impulse to the pendulum by the lateral arm 29 of the armature 19, the spark plug 46 will be intermittently fired for a length of time sufficient to insure the ignition of the gas at the burner 7. Thus, the gas valve 34 is opened simultaneously with the initiation of the vibration of the pendulum 33 (both being controlled by the armature 19), and thereupon the gas flows through the pipe 36 to the air mixer below the burner 7 and thence to the burner, whence it issues through the usual apertures in the burner. The firing of the spark plug must therefore continue until the gas issuing from the burner is ignited. The continued firing of the spark plug after such ignition of the gas is unnecessary, and the duration of vibration of the pendulum is preferably timed so that the firing of the spark plug continues only for a short time after the gas has been ignited.

The burning gas in the burner 7 heats the water passing through the coil 6 so that hot water issues from the faucet 9 as long as the burner 7 is lighted. The degree of heat transmitted to the water in the coil 6 may be controlled through the gas valve 35, which may be adjusted to admit any desired amount of gas to the burner 7 so that it will burn at any desired height of flame.

When sufficient hot water has been drawn from the faucet 9, the faucet is closed, and thereupon the flow of gas to the burner as well as the flow of water to the coil 6 is automatically shut off. When the faucet 9 is closed the pressure of the water on the upper side of the valve 11 will equalize the pressure on the lower side of the valve, and then the light spring 14 will force the valve into engagement with its seat 12, stopping the flow of water to the coil 6. The downward movement of the valve stem 11^a brings the insulated block 11^c into engagement with the movable member 16 of the master switch, swinging the switch member 16 out of engagement with the stationary switch member 15 and breaking the circuit then flowing to the primary windings of the transformer coils 37 and 38. When the transformer coils are thus de-energized the spring 40 swings the pivoted armature 39 away from the core of the transformer coil 37 and so lowers the latch member 41 so that its roller 42 is no longer within the notch 43 of the slidable armature 19 of the solenoid 18. Thereupon the coiled spring 20 forces the armature 19 from its innermost position as shown in Fig. 3 to its outer position as shown in Fig. 2. During the return movement of the arma-

ture 19 its arm 32 swings the gas valve lever 34 to shut off the flow of gas to the burner 7, and accordingly, the water within the coil 6 is no longer heated. The return movement 5 of the armature 19 is also utilized to return the slideable switch member 24 into engagement with the switch prong 25 to enable the re-energization of the solenoid 18 whenever the valve 11 is again opened by the flow of water after the faucet 9 is re-opened. The lateral arm 29 engages the upstanding lug 31 on the slideable switch member during the return passage of the armature 19 and slides the switch member 24 so that its outer extremity enters the switch prong 25. The lateral arm 29 also engages the upper extremity 32 of the pendulum 33 during its return movement, but since no current is passing through the transformer coils 37 and 38, the vibration of the pendulum 33 does no harm.

The controlling of the actuation of the several electrical mechanisms through the medium of the flow of water is the usual and desired method of control. But in the interest of safety I also provide means for the cutting off of the flow of gas to the burner 7 should at any time the flow of electric current to the apparatus be stopped through accident or malice. This will prevent a steam explosion within the coil 6 or outlet pipe 8 should the faucet 9 be closed and the burner 7 continue to heat the water then stationary within the coil 6. This electric safety means depends upon the position of the latching member 41 within the notch 43 of the armature 19. Since the latch member 41 is maintained in elevated position only as long as the swinging armature 39 is elevated, and the elevation of such armature continues only as long as the electric current flows through the primary winding of the transformer coils 37 and 38, the cessation of the current will automatically release the armature 39 from its raised position and permits its being lowered by the coil spring 40. The lowering of the armature 39 removes the roller 42 of the latch member 41 out of the notch 43 in the armature 19 and permits the coil spring 20 to return the armature 19 to its outermost position. During this return movement of the armature the gas valve lever 34 is swung to shut off the flow of gas to the burner 7.

The several electric actuating mechanisms may be suitably mounted within a container 60 which may be suspended, as by the screws 61, from the inlet pipe 10 or other suitable portion of the heater.

The extent of movement of the valve 11 when the faucet 9 is opened may be regulated by providing an adjusting screw 70 in the stationary switch member 15 to engage the block 11^a carried by the valve stem 11^a. This also controls the extent of move-

ment of the movable switch member 16 of 65 the master switch.

While it will be apparent that the illustrated embodiment of my invention herein disclosed is well calculated to adequately fulfill the objects and advantages primarily 70 stated, it is to be understood that the invention is susceptible to variation, modification and change within the spirit and scope of the subjoined claims.

Having described my invention, I claim: 75

1. In a water heater, a water pipe connected with a source of water supply, a gas burner arranged adjacent the water pipe, a valved supply pipe leading to the gas burner, and electrically actuated means for initiating the flow of gas to the burner under the control of the flow of water in the water pipe, including a solenoid coil arranged to be energized when the flow of water begins, an armature connected to the gas supply 85 valve and arranged to be moved upon the energization of said coil, and independent means for maintaining the armature in the attracted position, whereby the gas supply valve may be maintained in open position. 90

2. In a water heater, a water pipe connected with a source of water supply, a gas burner arranged adjacent the water pipe, a valved supply pipe leading to the gas burner, and electrically actuated means for 95 initiating the flow of gas to the burner under the control of the flow of water in the water pipe, including a solenoid coil arranged to be energized when the flow of water begins, an armature connected to the gas supply 100 valve and arranged to be moved upon the energization of said coil, means operated upon movement of the armature to de-energize said coil, and independent means for maintaining the armature in attracted 105 position after the de-energization of the coil as long as the water continues to flow.

3. In a water heater, a water pipe connected with a source of water supply, a gas burner arranged adjacent the water pipe, 110 a valved supply pipe leading to the gas burner, and electrically actuated means for initiating the flow of gas to the burner under the control of the flow of water in the water pipe, including a coil arranged to be 115 energized when the flow of water begins, an armature connected to the gas supply valve and arranged to be moved upon the energization of said coil, means operable upon such movement of the armature to de-ener- 120 gize said coil, and electrical means for holding the armature in its attracted position after the de-energization of said coil, including a coil and a movable member ar- 125 ranged to be attracted when the last men- tioned coil is energized, said movable mem- ber carrying a latch adapted to engage said armature.

4. In a water heater, a water pipe connected with a source of water supply, a gas burner arranged adjacent the water pipe, a valved supply pipe leading to the gas burner, and electrically actuated means for initiating the flow of gas to the burner under the control of the flow of water in the water pipe, including a coil arranged to be energized when the flow of water begins, an armature connected to the gas supply valve and arranged to be moved upon the energization of said coil, means operable upon such movement of the armature to de-energize said coil, and electrical means for holding the armature in its attracted position after the de-energization of said coil, including a transformer coil arranged adjacent said armature, a pivoted member adapted to be swung toward the transformer coil when energized, and a latch member mounted upon said pivoted member and adapted to engage said armature. 70
5. In a water heater, a water pipe, a gas burner arranged adjacent the water pipe, means under the control of the flow of water in the pipe for initiating the flow of gas to the burner, and means for igniting the gas at the burner including a spark plug mounted adjacent the burner, a spark coil connected with the spark plug, and means for energizing said spark coil, including vibrating mechanism controlling the passage of current to the spark coil and arranged to be set in motion by said first mentioned means. 75
6. In a water heater, a water pipe, a gas burner arranged adjacent the water pipe, means under the control of the flow of water in the pipe for initiating the flow of gas to the burner, and means for igniting the gas at the burner operable for a predetermined length of time after the operation of said first mentioned means, including a spark plug mounted adjacent the burner, a spark coil connected therewith, and means for intermittently energizing the spark coil including a vibrator adapted to be set in motion by said first mentioned means. 80
7. In a water heater, a water pipe, a gas burner arranged adjacent the water pipe, means under the control of the flow of water in the pipe for initiating the flow of gas to the burner, and means for igniting the gas at the burner operable for a predetermined length of time after the operation of said first mentioned means, including a spark plug mounted adjacent the burner, a spark coil connected therewith, and means for intermittently energizing the spark coil including a pendulum adapted to be rocked by said first mentioned means. 85
8. In a water heater, a water coil, a gas burner arranged beneath the coil, means for supplying gas to the burner whenever desired, and means for igniting the gas at the burner including a spark plug mounted adjacent the burner, a spark coil connected therewith, and means for intermittently energizing the spark coil, including a vibrator arranged to be set in motion when the flow of gas to the burner is initiated. 90
9. In a water heater, a water coil, a gas burner arranged beneath the coil, means for supplying gas to the burner whenever desired, and means for igniting the gas at the burner including a spark plug mounted adjacent the burner, a spark coil connected therewith, means for intermittently energizing the spark coil, including a transformer, normally open connections between the transformer and spark coil, and means for intermittently closing said connections, including a pendulum arranged to be rocked simultaneously with the initiation of the flow of gas to the burner. 95
10. In a water heater, a water coil, a gas burner arranged therebeneath, and means for supplying gas to the burner upon the initiation of the flow of water through the coil, including a valved gas supply pipe leading to the burner, a lever secured upon the valve, electrical means for rocking the lever, including a solenoid coil arranged to be energized upon the initiation of the flow of water through the coil, an armature connected with the gas valve lever and adapted to be attracted toward the solenoid when energized, means operated upon such movement of the armature for de-energizing the solenoid, and means for latching the solenoid in its attracted position controlled by the flow of water through the coil. 100
11. In a water heater, a water coil, a gas burner arranged therebeneath, and means for supplying gas to the burner upon the initiation of the flow of water through the coil, including a valved gas supply pipe leading to the burner, a lever secured upon the valve, electrical means for rocking the lever, including a solenoid coil arranged to be energized upon the initiation of the flow of water through the coil, an armature connected with the gas valve lever and adapted to be attracted toward the solenoid when energized, means operated upon such movement of the armature for de-energizing the solenoid, and electrical means for latching the armature in its attracted position arranged to be energized as long as the flow of water through the coil is continued. 105
12. In a water heater, a water coil, a gas burner arranged therebeneath, and means for supplying gas to the burner upon the initiation of the flow of water through the coil, including a valved gas supply pipe leading to the burner, a lever secured upon the valve, electrical means for rocking the lever, including a solenoid coil arranged to be energized upon the initiation of the flow of water through the coil, an armature connect- 110
13. In a water heater, a water coil, a gas burner arranged therebeneath, and means for supplying gas to the burner upon the initiation of the flow of water through the coil, including a valved gas supply pipe leading to the burner, a lever secured upon the valve, electrical means for rocking the lever, including a solenoid coil arranged to be energized upon the initiation of the flow of water through the coil, an armature connect- 115
14. In a water heater, a water coil, a gas burner arranged therebeneath, and means for supplying gas to the burner upon the initiation of the flow of water through the coil, including a valved gas supply pipe leading to the burner, a lever secured upon the valve, electrical means for rocking the lever, including a solenoid coil arranged to be energized upon the initiation of the flow of water through the coil, an armature connect- 120
15. In a water heater, a water coil, a gas burner arranged therebeneath, and means for supplying gas to the burner upon the initiation of the flow of water through the coil, including a valved gas supply pipe leading to the burner, a lever secured upon the valve, electrical means for rocking the lever, including a solenoid coil arranged to be energized upon the initiation of the flow of water through the coil, an armature connect- 125
16. In a water heater, a water coil, a gas burner arranged therebeneath, and means for supplying gas to the burner whenever desired, and means for igniting the gas at the burner including a spark plug mounted adjacent the burner, a spark coil connected therewith, and means for intermittently energizing the spark coil, including a vibrator arranged to be set in motion when the flow of gas to the burner is initiated. 130

ed with the gas valve lever and adapted to be attracted toward the solenoid when energized, means operated upon such movement of the armature for de-energizing the solenoid, and electrical means for latching the armature in its attracted position arranged to be energized as long as the flow of water through the coil is continued, including a

coil, a member arranged to be attracted toward the coil when energized, and a latch 10 mounted upon said member and arranged to engage the armature when in its attracted position.

In witness whereof I hereunto set my hand.

SAMUEL G. CRANE.
